UNITED STATES PATENT OFFICE.

HENRY T. MOODY, OF NEWBURYPORT, MASSACHUSETTS, ASSIGNOR TO VICTOR MANUFACTURING COMPANY, OF NEWBURYPORT, MASSACHUSETTS.

DOOR OR SHUTTER.

1,052,610.

Specification of Letters Patent. Patented Feb. 11, 1913.

Application filed March 22, 1912. Serial No. 685,417.

To all whom it may concern:

Be it known that I, HENRY T. MOODY, of Newburyport, in the county of Essex and State of Massachusetts, have invented a new 5 and useful Improvement in Doors or Shutters, of which the following is a full, clear, and exact description, reference being had to the accompanying drawings, forming a part of this specification, in explaining its 10 nature.

My invention relates to an improvement in doors or shutters and essentially to an arrangement whereby the doors or shutters may be brought automatically to a closed 15 position in case of fire.

The essential object of my invention is to provide such type of automatic closure as will not interfere with the ordinary opening or closing of the door; one, in other words, 20 that will become operative only in case of fire and will exert no influence upon the door under normal circumstances, so that the door may be left in any open position as occasion may require.

25 I have shown the automatic closure comprising the essential feature of my invention as applied to double folding doors to which it is especially applicable. It is customary in such doors that the inner edges 30 thereof overlap one another or interlock when the doors are in a closed position. It is accordingly necessary that the doors should close one before the other and I have therefore provided an arrangement 35 whereby such successive closing of the doors may be effected automatically.

Referring to the drawings:—Figure 1 shows in elevation double folding doors and combined therewith the controlling elements comprising my invention, those for effecting the automatic closure of the doors in case of fire being shown in an inoperative position. Fig. 2 is the same as Fig. 1 excepting that the elements for effecting the 40 automatic closure of the doors in case of fire are shown in an operative or released position. Fig. 3 shows in enlarged elevation a structural part shown in Fig. 1, and to which special reference will hereinafter 45 be made. Fig. 4 is a side elevation of the part shown in Fig. 3. Fig. 5 is a section taken on the line 5—5 of Fig. 3. Fig. 6 is essentially a plan of the device which 50 effects the proper successive closing of the double folding doors. Fig. 7 is an enlarged 55

plan of a part of such device, and Fig. 8 is a front elevation of the part shown in Fig. 7.

In the drawings:—1 represents double 60 folding doors.

2 represents the wall surrounding the doors and which for present purposes includes also the casing in which the doors are set.

Secured to each door at a point near the 65 top edge thereof and preferably near the front edge of the door is a bracket 3. This bracket projects outwardly and upwardly to a point above the top edge of the door. Connecting with this bracket is a chain 4 70 which renders over pulleys 5 and 6 and bears upon its end an overbalancing weight 7. Of these pulleys the pulley 5 is secured to the door casing or wall at a point just above the door and preferably just adjacent the 75 bracket 3 secured to it. The pulley 6 is mounted upon the shelf 8 of a bracket 9 secured to the wall beyond the rear side of the door and preferably at a point about in line with the top edge thereof. The chain 80 4 after passing over the pulley 6 connects with the weight 7 by passing through an opening in the shelf of the bracket.

The relative disposition and arrangement of the parts thus far described is such that 85 the weight 7 will act through the chain 4 to draw the door which it controls to a closed position. In the normal arrangements of the parts, however, the weight 7 is maintained in a raised position adjacent 90 the body of the bracket 9 just beneath the shelf 8. In such place the weight is positioned and centralized relatively to the bracket by means of a pin 10 which extends upwardly through its shelf 8. On the rear 95 side of the weight is a headed pin or screw 11 which, when the weight is raised to its elevated position as aforesaid, slides into the forked end 12 of the bracket. By these means the weight is loosely retained as 100 against lateral displacement on the bracket but so that it may fall or drop in a true vertical direction. The weight is maintained in its raised or elevated position as aforesaid in the following manner: Pivotaly secured to the face of the bracket 9 between it and the weight when in its raised position is a latch 13. This latch is a lever provided with a power arm 14 and right and left work arms 15. When the latch is turned 105 110

to an engaging position one or the other of these arms 15 (depending as the latch and the weight which it acts to retain are at the left or the right of the door) draws under 5 one or the other of pins 16 which project from the rear side of the weight, the latch turns acting to support the weight.

The latch is held in its engaging position supporting the weight by means of a flexible 10 connection or chain 17 having in it a thermostatic device 18, usually consisting of a fusible link which breaks in case of fire. The connection 17 may run to any place or 15 part of the building in which the door is located and where it is desired to set the fusible link. Where double folding doors are controlled as shown then of course the connections 17 will have a thermostatic device or link common to both connections in 20 order that both latches 13 may be simultaneously released by the fusing of the link in case of fire. According to the construction shown, where the link is arranged just above the doorway in which the doors to 25 be controlled are set, the connections 17 are passed through eyes or pulleys 19 fixed to the wall and thence downwardly to connect with the fusible link 18 held fixed by a cord or chain piece 20, common to both 30 main connections and secured to the casing just above the doors.

When the overbalancing weight 7 is held in its inoperative raised position as above described slack of course will be formed in 35 the chain 4 bearing the weight. This slack is taken up between the bracket 3 to which the inner end of the chain is secured and the pulley 5 over which the chain first renders, by means of a loop 21 formed in 40 the chain. The means employed for taking up the slack is by a take-up consisting of a chain or flexible connection 22 which is passed through the loop 21. One end of the take-up 22 is secured to the overbalancing 45 weight 7. The other end of this take-up is provided with a ring 23 which is slipped over the pin 10 which projects upwardly from the upper end of the weight and through the shelf 8, the ring being held by 50 the pin and resting on the shelf. With the parts thus arranged, with the weight held in a raised position, it will be observed that the parts exert no influence whatever upon the door to close it so that the door may be 55 left in any open position as desired. The only effect will be that when the door is opened the portion 24 of the chain 4 which forms that part of the loop in the chain which is secured to the door, will turn 60 with it, the loop having preferably such extension that the end of the loop will be in substantial alinement with the axis on which the door turns. The operation of the parts, however, in case of fire when the door is 65 open, is as follows: Assuming that the heat

has fused and broken the link 18, thereupon the connection or chain 17 is released which in turn no longer acts to hold the latch 13 in its engaging position for supporting the weight. Thereupon the weight will fall and draw away from the latch, causing the latch to turn out of engagement with the pin 16 of the weight. As the weight continues to fall the ring 23 on the end of the take-up 22 will be drawn off from the end 70 of the pin 10 by which it is held and the take-up will be drawn through the loop in the chain 4 releasing it, when the chain freed will through the influence of the overbalancing weight act to draw the door to a 75 closed position.

In order that the weight may not break away from the end of the chain when it is abruptly let fall I prefer to provide the weight with a compression spring 25 as 80 shown in Fig. 5 with which the end of the chain connects. The upper end of this spring bears against a shoulder 26 formed within the weight. The chain 4 passes through the weight and through the core of the spring and is secured to the lower end of the spring with the effect that as the weight falls the spring will be compressed and act as a buffer to the weight, thereby breaking the abrupt fall of the weight and eliminating 85 the danger of its breaking the chain.

The door-closing device or devices above described is illustrated as applied to double swinging doors which have overlapping inner edge portions as is customary in such doors and which accordingly require that the doors should close in proper sequence inasmuch as the automatic closure before described would release both doors to close at 100 the same time in case of fire. It is accordingly necessary to provide some means by which the doors may be automatically controlled to close in proper sequence, and to this means reference will now be made.

Secured to the wall or casing in which the 110 doors are set, just above and adjacent the front edge of the right hand door as shown, or the one which must close first, is a bracket 27. Pivotally secured to this bracket at the point 28 to turn on a vertical axis is an angular lever 29 having arms 30 and 31, respectively. Of these arms the arm 30 extends laterally alongside the casing while the arm 31 projects outwardly therefrom in an oblique direction. Secured to the top of 115 the left hand door adjacent the front edge thereof and projecting above the upper edge of this door is a stop 32. The size and arrangement of the lever 29 with respect to this stop is such that its arm 31 will engage the stop 32 and prevent a full closure of the left hand door; that is, until the lever and arm 31 thereof is moved into a disengaging 120 position when it will no longer engage the stop and the left hand door will be per- 125

mitted to close. The lever and arm 31 thereof is yieldingly held in engaging position by means of a compression spring 33 socketed within the arm 30 and bearing 5 against the adjacent wall or casing, the tension of the spring tending to normally turn the lever and hold the arm 31 thereof in a position to engage the stop as aforesaid. This position is defined by the inner end of 10 the arm 30 at the point 34 bearing against the wall or casing when the lever has been turned by the spring to a position where the arm 31 thereof will properly engage the stop, and which is the normal position of 15 the lever. Secured to the right hand door as shown and projecting upwardly beyond the upper edge thereof is an arm 35. This arm is so positioned relatively to the arm 30 of the lever 29 that as the right hand 20 door is moved to a closed position and just prior to its full closure the arm 35 will engage the end of the arm 30 of the lever 29, compressing the spring 33 and turning the lever into a disengaging position or one in 25 which the arm 31 of the lever will be moved into a position where it will no longer engage the stop 32 on the left hand door, so permitting this door to close. It will accordingly be seen that although both doors 30 be simultaneously released to close in case of fire, yet in no event can the doors interfere with one another during their closing, but must close in proper sequence, for before the left hand door can assume a closed 35 position the right hand door must be passed by the left hand door to a substantially closed position when the left hand door will be released to close after it.

Having thus fully described my invention, I claim and desire to secure by Letters Patent of the United States:—

1. The combination with a movable door or shutter, of an overbalancing weight, a flexible connection bearing said weight and 45 connecting with said door or shutter, means for supporting and guiding said flexible connection whereby said weight let fall from a raised position may close said door or shutter and whereby also slack may be 50 formed in said flexible connection when said weight is in a raised position irrespective of the open or closed position of said door or shutter, a device for holding said weight in a raised position, a releasable device for taking up and holding the slack in said flexible connection when said weight is maintained in a raised position, and means whereby said devices may be simultaneously released.

60 2. The combination with a movable door or shutter, of an overbalancing weight, a flexible connection bearing said weight, and connecting with said door or shutter, means for supporting and guiding said flexible connection whereby said weight let fall from

a raised position may close said door or shutter and whereby also slack may be formed in said flexible connection when said weight is in a raised position irrespective of the open or closed position of said door or shutter, a releasable means supporting 70 said weight in a raised position, and means releasable upon the fall of said weight for taking up and holding slack therein when said weight is maintained in a raised position. 75

3. The combination with a movable door or shutter, of an overbalancing weight, a flexible connection bearing said weight and connecting with said door or shutter, means for supporting and guiding said flexible connection whereby said weight let fall from a raised position may close said door or shutter and whereby also slack may be formed in said flexible connection when said weight is 80 in a raised position irrespective of the open or closed position of said door or shutter, said means comprising in part a pulley arranged at a point adjacent the front edge of said door when in a closed position and above said door, a device for holding said weight in a raised position, a device for taking up and holding the slack in said flexible connection between said door and said pulley when said weight is maintained 85 in a raised position, and means for controlling said devices whereby they may be simultaneously released. 90

4. The combination with a movable door or shutter, of an overbalancing weight, a 100 flexible connection bearing said weight and connecting with said door or shutter, means for supporting and guiding said flexible connection whereby said weight let fall from a raised position may close said door or shutter and whereby also slack may be formed in said flexible connection when said weight is in a raised position irrespective of the open or closed position of said door or shutter, said means comprising in part a 105 pulley arranged adjacent the front edge of said door and above said door when the same is in a closed position, a releasable device for maintaining said weight in a raised position, a connection comprising in part a 110 thermostatic link and connecting with said device for maintaining the same in an operative position to support said weight, and means for taking up the slack in said flexible connection between said door and said pulley when said weight is maintained in a 115 raised position, said means connecting with said weight whereby it may become released upon the fall thereof. 120

5. The combination with a movable door or shutter of an arm secured thereto adjacent the front edge of said door and extending upwardly therefrom above the top edge thereof, an overbalancing weight, a flexible connection secured at one end to said weight 125 130

and at the other end to said arm, pulleys over which said flexible connection runs, one of said pulleys being arranged adjacent said arm and another of said pulleys above said 5 weight whereby said weight may hang pendant therefrom, a lever pivotally arranged to engage said weight and hold the same in a raised position, a releasable connection for holding said lever in its engaging position, 10 and means connecting with said flexible connection for taking up and holding the slack therein between said arm and said pulley adjacent thereto when said weight is maintained in its raised position, said means being adapted to become simultaneously 15 released with said weight.

6. The combination with double folding doors and casing therefor, of a lever pivotally secured to said casing above said doors 20 and adjacent the front edges thereof, the same being pivotally arranged to turn upon a vertical axis, the said lever having arms

reversely arranged to extend alongside said casing, one of which arms is adapted to engage said casing when said lever has been turned to an engaging position and thence extend obliquely therefrom, a stop carried by one of said doors adapted and arranged to the end that the obliquely extending arm of said lever may engage said stop and prevent the closing of said door when said lever is maintained in its said engaging position, a tension device for normally maintaining said lever in its engaging position and an arm carried by the other of said doors adapted to engage said lever as said other door is closed and move said lever into a disengaging position with respect to said stop. 30 35
